ENCLOSED SWIVEL LIGHTING FIXTURE

Nathan R. Schwartz, Yonkers, N.Y., assignor to Naras Research Inc., New York, N.Y., a corporation of New York

Filed Nov. 28, 1958, Ser. No. 776,972

9 Claims. (Cl. 240—128)

This invention relates to electrical lighting fixtures and more particularly to a fixture of the type which includes a lamp shade having enclosed therein and rigidly secured thereto, a swivel assembly or unit adapted to vary the angular position of the shade.

It is well known to provide lighting fixtures with swivels adapted to give them an angular or rotative adjustment. Such swivel assemblies are most desirably constructed so that it is not too difficult for the user to move the lamp to the desired position and, at the same time, the swivel is sufficiently firm so that the position of the lighting unit does not change when it is desired to keep it in a fixed position.

Typical swivel unit assemblies are known and are, for example, described in applicant's patents Nos. 2,643,144 and 2,362,100. Prior to the present invention, however, it has not been possible to economically incorporate a swivel unit of this general nature into a lamp shade so that the unit is enclosed within the shade, and does not project from any portion thereof. As will be hereinafter more apparent, such an arrangement has many mechanical and constructional advantages and, at the same time, provides a fixture having a clean looking, functional outward appearance.

Accordingly, it is an object of the present invention to provide a swivel mounted lighting fixture which is economical to manufacture, and yet is adapted to conceal the swivel portion thereof in such a manner as to increase the structural strength thereof and not apply any undue stresses to any of the component parts thereof.

Another object of the present invention is to provide an enclosed swivel unit in which all parts are secured so that no undesired relative movement between such parts occurs when it is desired to reposition the lamp by a movement imparted to the swivel unit.

These and other objects of this invention will become apparent when taken in connection with the drawings and the following description in which:

Figure 1 is generally illustrative of a typical lampshade in which the swivel unit is enclosed in accordance with the present invention.

Figure 2 is an enlarged cross-section view of the fixture shown in Figure 1 which illustrates in detail the construction of the swivel and shade assembly, and the means for securing the swivel within said shade.

Figure 3 is illustrative of the type of swivel unit which may be secured within the lampshade as hereinafter described.

Figure 4 is an exploded view showing the sequence and arrangement by which the swivel unit is secured to the shade member through the use of an intermediate mounting flange member.

Figure 5 illustrates in detail the serrated neck portion of the mounting flange member and its relationship to the corresponding part of the shade before the two are joined together.

Figure 6 is similar to Figure 5 and shows the relationship of the shade and mounting flange after joining.

2

Figure 7 is a cross-sectional view of Figure 2 taken along the lines 7—7 and looking in the direction of the arrows. This figure provides a view of the swivel unit and mounting means therefor as it would appear when looking into the open end of the shade with the light bulb socket removed.

Figure 8 is a cross-sectional view of Figure 2 taken along the lines 8—8 and looking in the direction of the arrows. This view illustrates the alignment between indentations in the swivel unit and mounting flange which is effective in rigidly securing the respective members to each other and thereby prevent any relative rotation between such members.

Generally, the present invention provides, in an electrical lighting fixture, a lamp shade having an enclosed swivel assembly secured thereto, at the end thereof, where the bulb is secured, i.e. the neck or smaller end. The entire swivel assembly lies within the contours of the shade. Extending from the swivel assembly through an opening in the shade is a suitable conduit which provides means for imparting both angular and rotative movement to the swivel and which also acts as an enclosure for electrical wiring.

The swivel unit is secured to the shell or shade by means of a mounting flange member. In accordance with the present invention, any well known swivel unit having the desirable features herein above referred to may be utilized. An example of such a swivel is illustrated in Figure 3 and will hereinafter be described in more detail. The mounting flange generally comprises a cup portion adapted to fit over the swivel unit and rigidly engage the same, and a flared frusto-conical member which abuts the inside surface of the lampshade. The mounting flange at the neck or narrow end thereof preferably terminates in a plurality of radially extending serrated projections, the function of which will now become evident.

In assembling the unit, the outer shade or shell member is beaded under compressive pressure so that it is bent around and engages both surfaces of the serrated projections of the mounting flange. This causes an engagement of the spaces between the teeth of the serrations which provides a tight, frictional grip between the mounting flange and shade and prevents turning of the mounting flange with respect to the shade when a rotative force is applied externally to the shade or to the conduit member extending from the neck of the shade.

The wider frusto-conical section of the mounting flange has, cut therefrom, a pair of tabs which may be bent sharply inwardly against the corresponding portion of the swivel unit, and firmly engage the swivel unit so as to prevent any rotation between the said swivel unit and mounting flange. Further means for preventing such rotation are provided by aligned longitudinal slots in both the shell of the swivel unit and the mounting flange.

Referring now to the drawings in detail, it is seen that the present assembly comprises generally a shade member 10 having secured to the neck or narrow end thereof a swivel assembly generally designated as 13 with a suitable arm 12 extending therefrom. The swivel shell member is designated as 14. While details of the specific swivel form no part of the present invention, it can be seen from Figure 3 that a suitable swivel would also generally include a ball assembly 60, a cup washer 61, spring 62 for forcing the ball firmly into the shell, and a retaining washer 63, all of which are retained in place by a circular indentation of the shell at 64.

The swivel shell 14 contains a plurality of longitudinal slots 15 which are aligned with similar slots 16 provided in the mounting flange member. Alignment of the cup-shaped portion 18 of the mounting flange with the slotted swivel shell is illustrated in Figure 8.

The swivel is secured within the contours of the shade

by a mounting flange. The mounting flange in addition to having cup shaped portion 18, is outwardly flared, has a radial surface 38 and terminates in a frusto-conical section 20, the outer surface of which is adapted to abut the inner surface of the shell 10. The mounting flange may, if desired, be welded to the shell at this point, although the structure is otherwise considered sufficiently rugged so that this is not necessary.

The narrow end or neck of the mounting flange preferably terminates in a plurality of radially extending serrated sections 22 which are compressed when the shell 10 is beaded, as shown in Figure 2. The beading takes place under sufficient compressive pressure so as to create plastic flow of the terminal edge 26 of the shell into the interstices between the serrated projections 22. The serrations thus prevent rotative motion of the mounting flange 18 with respect to the shade 10 by "locking" the two together through the frictional force provided in the compression of the edge of the shell member and mounting flange.

The appearance of the shell 10 and mounting flange 18 before and after the compression or beading operation is best illustrated in Figures 5 and 6, Figure 5 showing the serrations 22 by means of dotted lines, and Figure 6 showing the appearance of the terminal edge 30 of shade 10 as it appears after compression. It should be apparent that the beading could also be effected by bending the serrations 22 outwardly over the shell, and moreover, even without serrations on the neck of the mounting flange, a compressive force applied between the edges of the mounting flange and shade could effect a reasonably secure joining of the two.

The shade or shell 10 is provided with a slotted opening 32, as illustrated in Figure 4. This slotted opening provides for the passage of arm 12 which is illustrated in the form of a nipple having a threaded end 33. The slot is of such length as to allow for the desired angular movement of the swivel member by applying pressure to the externally extending nipple or to the shade. Most swivels are designed to provide an angular movement of about 90°.

When the mounting flange is secured to the shell, the next stage in assembling the unit calls for insertion of the swivel unit which is illustrated in Figure 4 as being contained within shell 14. The swivel is provided with a pair of slots 34 which can be engaged by tabs 35 which are cut from the mounting flange, and which result in slots of similar size in the surfaces 20 and 38 of the said mounting flange. The tabs 35 may be bent inwardly into slots 34 so as to firmly engage the swivel unit, the completed assembly having the appearance indicated in Figure 7 when viewed from the open end of the shell.

It is necessary, of course, for the mounting flange to have an opening 41 which will correspond to the slotted opening 32 of the shade or shell member. These openings may be provided by a single cutting operation after the mounting flange and shade are assembled. A corresponding slot 43 appears in the shell member which contains the swivel unit. Alternatively, these slots can be cut separately and then aligned in the assembly operation.

As previously mentioned, it is also necessary to align slots 15 and 16. Thus, the swivel shell and mounting flange are rigidly secured not only by tabs 35 fitting into slots 34, but also by means of the aligned longitudinal slots 15 and 16. After the parts are assembled, the swivel unit may, of course, be supplied with a conventional lighting fixture socket which, in the case of larger units, would be a porcelain socket. The socket can be screwed into threaded hole 50 located in the end of the swivel unit.

In prior devices wherein the swivel units are external to the shade the light socket would ordinarily be secured to the external swivel unit through the shell by means of a pair of screws. When an external force was applied to the shade or external swivel unit so as to effect a de-

sired movement, the resulting stresses were borne primarily by the relatively weak connecting screws.

In the foregoing, this invention has been described only in connection with preferred embodiments thereof. Many variations and modifications of the principles of the present invention within the scope of the description herein are obvious. Accordingly, it is preferred to be bound not by the specific disclosure herein, but only by the appending claims.

10 I claim:

1. In an electrical lighting fixture, a shade having a neck at one end and an open light-emitting portion at the other end, said shade having a swivel assembly enclosed therein, the swivel assembly being rigidly secured to a mounting flange, said mounting flange being disposed within the contours of said shade and being secured to the neck of said shade; an arm for enclosing electrical wiring extending from said swivel assembly through an opening in the neck of said shade; the said swivel assembly being adapted to permit relative movement of said shade with respect to said arm.

2. In an electrical lighting fixture, a shade having a neck at one end and an open light-emitting portion at the other end, said shade having a swivel assembly enclosed therein, the swivel assembly being rigidly secured to a mounting flange, said mounting flange being disposed within the contours of said shade and having a cup-shaped section surrounding the swivel assembly and being held in intimate engagement therewith, said cup-shaped section terminating in a neck which is secured to the neck of said shade; an arm for enclosing electrical wiring extending from said swivel assembly through an opening in the neck of said shade; the said swivel assembly being adapted to permit relative movement of said shade with respect to said arm.

3. In an electrical lighting fixture, a shade having a neck at one end and an open light-emitting portion at the other end, said shade having a swivel assembly enclosed therein, the swivel assembly being rigidly secured to a mounting flange, said mounting flange being disposed within the contours of said shade and having a cup-shaped section surrounding the swivel assembly and being held in intimate engagement therewith, said cup-shaped section terminating in a neck which is compressively beaded to the neck of said shade; an arm for enclosing electrical wiring extending from said swivel assembly through an opening in the neck of said shade; the said swivel assembly being adapted to permit relative movement of said shade with respect to said arm.

4. In an electrical lighting fixture, a shade having a neck at one end and an open light-emitting portion at the other end, said shade having a swivel assembly enclosed therein, the swivel assembly having a shell rigidly secured to a mounting flange, said mounting flange being disposed within the contours of said shade and having a cup-shaped section surrounding the swivel assembly and being held in intimate engagement therewith, said cup-shaped section terminating in a neck having radially extending serrated projections, said neck being rigidly secured to the neck of said shade by compressive beading and frictional engagement between said shade neck and serrated projections; an arm for enclosing electrical wiring extending from said swivel assembly through a slotted opening in the neck of said shade; the said swivel assembly being adapted to permit relative movement of said shade with respect to said arm.

5. The lighting fixture set forth in claim 4 in which the mounting flange includes an outwardly flared frusto-conical section secured to said cup-shaped section by a radial extension, the terminal edge of said flared section abutting the internal surface of the shade.

6. The lighting fixture set forth in claim 5 in which the frusto-conical section of the mounting flange includes a pair of tabs bent inwardly over corresponding slots in the shell of the swivel assembly.

7. In an electrical lighting fixture, a shade having a neck at one end and an open light-emitting portion at the other end, said shade having a swivel assembly enclosed therein, said swivel assembly having a shell rigidly secured to a mounting flange, said mounting flange being disposed within the contours of said shade and having a cup-shaped section surrounding the swivel assembly and being held in intimate engagement therewith by means of aligned slotted indentations in the shell of said swivel assembly and in said cup-shaped section, said cup-shaped section terminating in a neck having radially extending serrated projections, said neck being rigidly secured to the neck of said shade by compressive beading and frictional engagement between said shade neck and serrated projections; an arm for enclosing electrical wiring extending from said swivel assembly through a slotted opening in the neck of said shade; the said swivel assembly being adapted to permit relative movement of said shade with respect to said arm.

8. The lighting fixture set forth in claim 7 in which the mounting flange includes an outwardly flared frusto-conical section secured to said cup-shaped section by a radial extension, the terminal edge of said flared section abutting the internal surface of the shade.

9. The lighting fixture set forth in claim 7 in which the frusto-conical section of the mounting flange includes a pair of tabs bent inwardly over corresponding slots in the shell of the swivel assembly.
